CONDENSER

Filed June 19, 1922

UNITED STATES PATENT OFFICE.

LAWRENCE D. McEWEN, OF DES MOINES, IOWA.

CONDENSER.

Application filed June 19, 1922. Serial No. 569,528.

To all whom it may concern:

Be it known that I, LAWRENCE D. McEWEN, a citizen of the United States, residing at Des Moines, in the county of Polk and State of Iowa, have invented certain new and useful Improvements in Condensers, of which the following is a specification.

This invention relates to condensers especially adapted for application to automobiles.

Briefly stated an important object of this invention is to provide a radiator attachment having simple and reliable means whereby to condense the vapors created in the cooling system of an automobile, thereby dispensing with the necessity of employing the breather pipe now widely used in connection with automobiles.

By the use of this invention the alcohol and other vapors created are quickly condensed and returned to the radiator without loss so that the liquid may be again circulated through the engine for cooling purposes.

Further the invention forming the subject matter of this application aims to provide a condenser which may be readily and conveniently applied to automobiles without changing the construction of the same and without marring the appearance of the vehicle.

A further object is to provide a condenser for automobile radiators which is neat in appearance, cheap to manufacture and of highly simplified construction.

Other objects and advantages of the invention will be apparent during the course of the following description.

In the accompanying drawing, Figure 1 is a perspective illustrating the application of the improved condenser.

Figure 2 is a vertical sectional view through the same applied.

Figure 3 is a horizontal sectional view taken on line 3-3 of Figure 1.

In the drawing wherein for the purpose of illustration is shown a preferred embodiment of the invention the numeral 5 designates an automobile radiator having the usual nipple 6 to which the cap 8 of the condenser is attached. Figure 2 illustrates that the lower portion of the cap is in the nature of an annular flange interiorly screw threaded for engagement with the nipple 6 whereby the condenser may be attached to

the radiator without in any way altering the construction of the same.

In carrying out the invention the cap 8 is provided with a cone-shaped bottom 10 welded or otherwise secured to the inner wall of the cap at a point above the screw threads thereon and the upper portion of the cone-shaped bottom is secured to the top of the cap and communicates with an outlet pipe 11. The outlet pipe 11 extends through the top of the cap 8 and has its upper end formed with a nozzle 12 which discharges the vapor or steam as the case may be into a header 14 of semi-bulbous formation.

A plurality of return pipes 16 are connected to the header 14 and have their lower ends extended through the top of the chamber or cap 8. The lower ends of the return pipes 15 communicate with a return chamber 18 of annular formation and the return chamber is provided with a plurality of outlet pipes 20 which permit the condensed liquid to return to the cooling system of the engine.

In case the pressure of the steam exceeds a predetermined point, the relief valves 25 are automatically opened so as to permit this excess steam to be discharged. Any number of the relief valves 25 may be extended through the top of the cap 8 and the valves 25 of course have communication with the annular chamber 18.

With reference to the foregoing description taken in connection with the accompanying drawings it will be seen that the cone-shaped bottom wall 10 not only serves as a bottom of the annular chamber 18 but also as a means to direct the steam into the outlet pipe 11.

The improved condenser may be applied to a motor vehicle without in any way altering the construction of the same and without marring the appearance of the vehicle.

Having thus described the invention, what is claimed is:—

1. A condenser for automobile radiators comprising a cap having means whereby the same may be secured to the nipple of a radiator, a cone-shaped bottom wall arranged within said cap and having its outer edge secured to the cap at a point spaced intermediate the upper and lower ends of the same, the apex of the cone-shaped bottom wall being connected to the top of the cap, an outlet pipe having communication with

the apex of said bottom wall and having its upper end formed with a nozzle, a header receiving the nozzle of said pipe, a plurality of return pipes connected to said header, the 5 lower ends of said return pipes being connected to said cap.

2. A condenser for automobile radiators comprising a cap having means whereby the same may be secured to the nipple of a radiator, a cone-shaped bottom wall arranged within said cap and having its outer edge secured to the cap at a point spaced intermediate the upper and lower ends of the same, the apex of the cone-shaped bottom 10 wall being connected to the top of the cap,

an outlet pipe having communication with the apex of said bottom wall and having its upper end formed with a nozzle, a header receiving the nozzle of said pipe, a plurality of return pipes connected to said header, the 20 lower ends of said return pipes being connected to said cap, and relief valves connected to said cap.

In testimony whereof, I have affixed my signature in the presence of two witnesses. 25

LAWRENCE D. McEWEN.
